UNITED STATES PATENT OFFICE.

FOREST CHENEY, OF CHICAGO, ILLINOIS.

DESIGN FOR AN AMPLIFYING-HORN FOR SOUND-REPRODUCING MACHINES.

45,738.

Specification for Design.

Patented May 12, 1914.

Application filed February 13, 1913. Serial No. 748,247. Term of patent 14 years.

To all whom it may concern:

Be it known that I, FOREST CHENEY, a citizen of the United States, and a resident of Chicago, in the county of Cook and State of Illinois, have invented a new, original, and ornamental Design for an Amplifying-Horn for Sound-Reproducing Machines, of which the following is a specification.

To illustrate my invention, I annex hereto a sheet of drawings, in which,—

Figure 1 is a perspective view of the horn; Fig. 2 is a plan view in central horizontal section; Fig. 3 is a side elevation in central

vertical section; and Fig. 4 is an end elevation.

I claim:

The ornamental design for an amplifying horn for sound-reproducing machines, as shown.

In witness whereof, I have hereunto set my hand and affixed my seal, this 3rd day of February, A. D. 1913.

FOREST CHENEY. [L. S.]
